UNITED STATES PATENT OFFICE.

BRYSON D. HORTON, OF DETROIT, MICHIGAN.

LOCKING DEVICE FOR SWITCHES.

1,129,570.

Specification of Letters Patent. Patented Feb. 23, 1915.

Application filed November 1, 1913. Serial No. 798,680.

To all whom it may concern:

Be it known that I, BRYSON D. HORTON, a citizen of the United States, residing at Detroit, in the county of Wayne and State 5 of Michigan, have invented certain new and useful Improvements in Locking Devices for Switches, of which the following, taken in connection with the accompanying sheet of drawings, is a full, clear, and concise de- 10 scription.

This invention relates more particularly to electrical switches of the iron clad type, in which switch contacts are mounted within a metallic casing. In one type of switch 15 of this general character, the stationary contacts are fastened to the base of the receptacle, while the coöperating movable contacts are attached to and carried by a hinged cover, a suitable operating member extending 20 through the cover to permit of exterior manipulation.

The principal object of my invention is to provide a locking mechanism, coöperating with the exterior operating member of the 25 switch, to lock the contacts in separated or off position, by preventing the movement of the operating member, when the lock mechanism is applied thereto.

In the drawings: Figure 1 is a view in 30 side elevation of an iron clad switch incorporating my present invention. Fig. 2 is a front view thereof taken on lines *a—a* of Fig. 1. Fig. 3 is a detail view in plan of the operating member, together with the coöperating lock mechanism.

In detail the iron clad switch comprises a metallic housing, consisting of a body or receptacle portion 1 and a cover or top portion 2 suitably hinged at 3 to the body portion. Mounted upon the base of the receptacle 1 is a block of insulating material 4 carrying the stationary jaw contacts 5. Mounted in the cover and adapted to reciprocate therethrough are reciprocating plungers 6 carrying at their inner ends a cross-head 7 to which are attached knife blade contacts 8. At the opposite ends of the plungers 6 is a cross-head 9 held in place by suitable nuts 10. This cross-head has formed integral 45 therewith a knob or handle 11 by means of which the movable contacts are operated. 12—12 indicate bosses or extensions forming bearings for the plungers. These extensions are formed integral with the top 2 50 of the receptacle. It will be understood that

when the handle 11 is operated to bring the contacts into coöperative position the cross-head 9 will rest upon the extensions 12, the latter serving to limit the downward movement of the mechanism. When the electrical connection is broken between the contacts the handle is pulled outwardly reciprocating the plungers 10 in like direction. Thus a gap is created between the extensions 12 and the cross-head 9. In 60 this gap between the extensions and cross-head I position a U shape metallic member of spring like material 13 of sufficient size to substantially envelop the plungers 6 at the same time engaging the extensions 12 and cross-head 9. This metallic member 13 is provided with perforations or apertures 14 adjacent the free ends, but terminating inwardly of the outer edge of the plunger 6, which is nearest the said free 65 ends, so that the bow 15 of a suitable pad lock may be inserted in such manner as to straddle the said plunger. When the U shape member 13 is so positioned and the lock manipulated in the manner described, 70 the plungers are prevented from being reciprocated in their usual manner for making connection between the contacts within the receptacle. Thus effective locking means 75 is provided for the switch to prevent unauthorized manipulation. The pad lock and U shape locking plate are connected together by means of a suitable chain 16 preventing their separation and the possible 80 loss of one or the other.

While I have described one specific form of locking mechanism for accomplishing the result sought, to wit: the locking of the plunger contact operating mechanism in its off position, I do not wish to be understood 85 as limited to the precise details of construction shown and described, but on the contrary wish to reserve to myself a fair range of equivalents commensurate with the scope of the appended claims and the state of the 90 existing prior art.

Having thus described my invention what I claim as new herein and desire to secure by Letters Patent is:

1. A lock device for locking a member 105 which reciprocates in and out of a casing in its outwardly reciprocated position comprising a pair of members provided with apertured free ends adapted to coöperate with the reciprocating member, and a lock 110

adapted to pass through the apertures in the ends and around the reciprocating member and prevent movement thereof.

2. In combination with members mounted 5 to reciprocate in and out of a casing, a lock device adapted to coöperate therewith to lock said members in outwardly reciprocated position, comprising a substantially U-shaped member provided with aligned apertures extending through and adjacent the free ends thereof and a removable lock pro-

vided with a bow adapted to pass through the apertures and extend around the free ends thereof, substantially as described.

In witness whereof I have hereunto set 15 my hand in the presence of two subscribing witnesses this 29th day of October, 1913.

BRYSON D. HORTON.
